Letter Patent

Mr. Justice referred to me these Letters Patent and making full of the same
containing a description in the words of the said Federick Richards
for machine for pulling dry Woods.

This machine is a horizontal wheel with four
spokes, the spokes are made fast to the wheel in the form of plow iron standing
in a miter. I have observed that the wheel can be made on a large scale or
a small one to answer a good purpose. The wheel can be made of iron or iron
but for common Woods I have a pair of iron on a wooden spoke, and
when the bearing is carried on a large scale then the wheel may be made
of wood. The wheel or guard is to be made with a hole of twelve or one
spoke to something solid that will stand the force of the wheel and not
umble by going above the wheel and lying so close to the wheel that the friction
may be even with a pair of iron on a small scale to prevent the wood
The wheel of iron may be perpendicular or horizontal turning the beam
on the edge or side. but I prefer a horizontal wheel having the beam
on the side on a miter. The method of holding the dry stuff, the common
man clothes is calculated to be held by hand but when the bearing
is carried on a large scale I think a large or broad set shall
hold the dry Woods on a miter or more perspective as may best suit
the purpose.
